UNITED STATES PATENT OFFICE

FERNAND BELISLE, OF OTTAWA, ONTARIO, CANADA

SORTER-COUNTER MACHINE

Application filed November 8, 1929. Serial No. 405,740.

This invention relates to a machine for sorting, counting and tabulating punched cards, usually known as a sorter-counter machine.

5 The primary object of this invention is to improve on such known machines, by speeding up the number of cards passed through the machine, by more effective mechanisms, and by a simpler construction.

10 Another object is to especially adapt such a machine for census work.

Another object is to so design such a machine that it can be easily adapted for use in conjunction with an adding machine, as for 15 instance the "Burroughs", for purposes of tabulating alone, or both tabulating and printing.

Still another object is to substitute air under pressure as a medium for operating the 20 counters of such machines, in lieu of direct mechanical connections or electro-magnets as now used on all well known such machines. By so using air, the element of uncertainty of operation ever present where electricity is 25 used, through short circuiting for instance, is eliminated, and a machine of less complicated construction can be built to replace those depending on direct connections to operate the counters.

30 Other objects will appear as the specification is read in the light of the drawings.

In the drawings and specification to follow, an acceptable form of my invention is disclosed, but it is to be understood that I am not 35 to be limited to that exact disclosure, and I wish to secure such other forms and modifications as fall within the scope of the appended claims.

40 In the drawings:

Figure 1 is a fragmentary side elevation of a sorting machine made in accordance with my invention, showing also a portion of a tabulator operated in conjunction with the sorting machine;

45 Figure 2 is a plan view of Figure 1, but without the tabulator;

Figure 3 is a perspective view of the sorter head;

50 Figure 4 is a perspective view of the control block;

Figure 5 is a part-side elevation and part section of the control block;

Figure 6 is a top plan view of the bolt locking the carriage cams;

Figure 7 is a top plan view of the lever actuating the locking bolt shifting lever;

Figure 8 is a side elevation of one of the catches locking the valve lever;

Figure 9 is a perspective view of one of the cam carriages or blocks;

Figure 10 is a side elevation of one of the carriage cams;

Figure 11 is a front elevation of Figure 9;

Figure 12 is a fragmentary top plan view of one of the endless chains mounting the cam carriages;

Figure 13 is a perspective view of a link of the endless chains;

Figure 14 is an assembly showing a number of air pistons and other related parts used in conjunction with the sorter;

Figure 15 is a side elevation taken approximately on line 15—15 in Figure 16;

Figure 16 is a top plan view of Figure 14;

Figure 17 is a fragmentary front view of the valve board or system operatively connecting the sorter counters to the tabulator counters;

Figure 18 is a side elevation of Figure 17;

Figure 19 is a fragmentary elevation view of the valve rod;

Figure 20 is a section on line 20—20 in Figure 17, with valve rod not shown;

Figure 21 is a diagram showing method of operatively connecting sorter counters to the tabulator counters;

Figure 22 is a section taken on line 22—22 in Figure 3;

Figure 23 is a top plan view of the clip operating the carriage cam-locking device;

Figure 24 is a side elevation of a carriage cam-operated clip;

Figure 25 is a side elevation of a carriage operated clip;

securing the cam operated clips to their respective deflecting plate shafts;

Figures 28A to 30 illustrate the application of my invention to an adding machine.

In the drawings, like numerals of reference indicate corresponding parts in the various figures.

The cards to be fed through the machine are stacked on the floor 20 of what is known as the card box, this box being located at the front end of the sorter head, and consisting merely of a rectangular space defined by upright members, as for instance (see Figure 3), side members 11 secured to the sorter head 10, front clips 12 slightly inclined rearwardly, and upright members 13 carried by cross-wise bars 14 secured to the sorter head. The cards are fed into the bite of feed rollers 15, by blocks 16 known as feed knives which are mounted to slide on rods 17, the knives being reciprocated on their rods (see Figure 22) by cranks 18 turning on eccentrics 19 fixed to a shaft 19A; the cards are thus fed one by one through the throat or clearance between the members 13 and the floor 20 and into the bite of the feed rollers. Such a card box as just described, the knives and the means of actuating the same, are well known and are now used on a number of sorting machines, as for instance the Powers and the Hollerith machines.

The movement forwardly of each card becomes checked shortly after it leaves the card box, by engaging with what is called a gate 21 mounted to lower into the path of the card and subsequently rise to allow the card to resume its forward travel through the machine; this gate, which slides in grooves 22 between two spaced upright members 23, is normally held in a raised position by springs 24, and is lowered by a lever 25 pivoted to a cross member 26 secured in the head 10, the lever, which carries a roller 27, being swung downwardly to lower the gate by the action of a cam 28 fixed on a shaft 29 and riding on the roller 27. The shaft 29 is operatively connected to the shaft 19A in a manner to be described later, in such a way that for every complete stroke forwardly and rearwardly of the knives 16, the gate will lower and rise, the gate being thus lowered and raised for every card ejected from the card box; the cam 28 is also so formed that the gate remains in the path of the card only so long as is required to permit the sorter head 30 to perform its intended function.

After leaving the sorter head, following the rising of the gate, the card continues its travel forwardly to be eventually discharged out of the machine or stored in sorting receptacles or compartments.

The sorter head 10 is firmly secured to suitable brackets 31 resting either on a table

or on the floor; in the head is mounted the control block 30.

The block 30 is mounted to alternately lower and rise, lowering to engage a perforated plate or card rest 32, or a card when one is stopped by the gate after its ejection from the card box, and rising to disengage the plate, or the card, as the case may be, the card resuming its forward travel as the gate rises. The perforated plate 32 is on a level with the floor 20 of the head 10 and extends to within a short distance of the gate.

The block 30 has three rollers on each side, rollers 33 arranged in pairs to ride on the side faces of upright guide members 34 secured to the head 10, and single rollers 35 arranged to ride on the inner faces of the guide members; the block is thus free to rise and lower within the head and its movement is constrained to a vertical one while the block is maintained substantially in a plane parallel with the plane of the perforated plate.

The block is normally held clear of the perforated plate, as with springs 36 (see Figure 2) fastened at one end to brackets 37 secured to the block and at the other end, in brackets 38 fastened to the sorter head 10. As shown, the block is lowered by the action of cams 39, two fixed to a shaft 40 and two fixed to the shaft 29, the cams engaging four rollers 41 journalled in the ends of members 42 mounted above the block; the cams are formed to lower the block and retain same in co-operative engagement with the perforated plate only so long as is required to permit the block to perform its function.

The function of the block 30 is one of control, controlling the instrumentalities which operate the devices counting the cards or causing the cards to be sorted. In the present form of my invention, air under pressure is utilized as a means or agent for operating these devices, and the air from a suitable source (not shown) is allowed to enter a chamber or cavity 43 (see Figure 5) in the block, or the flow thereinto checked, by the action of a valve 45 secured on the block. The valve stem 46 has a branch 47 operatively connected to the source by a flexible hose 47A, the valve plunger 48 being raised and lowered by the action of a pivoted lever 49; as shown, the lever is pivoted in brackets 50 and is operatively connected to the valve plunger 48 by links 51 and pins 52 and 52A.

The valve opens as the plunger rises in the stem, and closes to check the supply of air as the plunger lowers to its normal or closed position; dogs 53 pivoted as at 54 in brackets 55 secured to the block or more particularly to one of the members 55A mounting the rollers 33 and 35, are formed and mounted to co-operate with the lever 49 to

lock the same in a position corresponding to the closed position of the valve, and to release the lever to permit of the same swinging to open the valve and therefore admit air into the air chamber 43. The lever is thus locked by the dogs which have a spring 57 tied and tensioned therebetween, the dogs swinging inwardly into the path of the lever when raised, until their lower cam portions 58 engage with pins 59 mounted to slide through the block; the dogs are swung outwardly against the action of the spring 57 as the lever swings downwardly and engages the slanting top edges 60 (see Figure 8).

A spring 61 (see Figure 2), tied at one end in a bracket 62 secured to the outer end of the lever 49 and at the other end, in a bracket 63 secured to the cross member 26 of the sorter head 10 and at a lower elevation than the bracket 62, is tensioned to exert a pull downwardly on the outer end of the lever and thus normally retain the other or inner end of the lever releasably locked by the dogs 53.

The lever 49 carries a roller 64 positioned to engage with or ride on a cam 53B fixed on the shaft 29 when the block 30 lowers to engage a card on the perforated plate 32, the cam being formed with a notch 53A allowing the outer end of the lever 49 room to swing downwardly under the action of the spring 61 as the dogs swing outwardly to release the inner end of the lever. The lever will not swing to open the valve unless the dogs 53 are swung outwardly to release the same, by the action of the pins 59 which are slidably mounted and in engagement with the cam portions 58 of the dogs.

The function of the pins 59 is to operate the dogs outwardly to release the lever 49 and therefore allow the valve to open, when a card is in position upon the perforated plate, but to lock the lever to keep the valve from opening when no card has been delivered to the perforated plate; the pins are so positioned in the block and away from the gate, that they will engage any card in position upon the plate 32, but they will simply enter two correspondingly-positioned holes 66 in the plate when there is no card in position under the descending block 30. Obviously, the pins 59 normally project below the lower face of the block 30 so that they may be actuated upwardly when the block engages a card. The pins 59 are normally held in inoperative position by springs 59A secured under the member 55A and tensioned to exert a downward pressure on the pins, the top of which they engage; the downward movement of the pins is determined by the provision of a shoulder formed by an enlarged portion 59B (see Fig. 26).

From the air chamber 43 are a number of air passages or discharge outlets 68, spaced

to align with an equal number of holes or discharge outlets 69 through the plate 32, and from the plate 32 depend air conduits 70 leading to air-operated counters. When the block 30 has been lowered to engage a card now in position and stopped on the plate 32, the valve has operated to allow air to flow into the air chamber 43 and from the chamber, into the conduits corresponding to the holes in the card, and finally to the counters; the valve is closed as the block again is raised, the air in the chamber being exhausted through the holes 68. As many counters will be then operated by the flow of air as there are holes in the card.

Obviously, as many holes 68 and 69 are provided as the maximum number of holes that may be punched through the cards and these spaced to align or correspond with one another.

The cards may be sorted or collected into a number of compartments, to thus form groups of same characteristics, after each leaves the sorter head, and the number of cards in each group added by a separate counter.

The counters 72, 72A, 72B, etc., thus used in connection with the sorting compartments 73, 73A, 73B etc. respectively, are independently operated and register the number of cards destined to the respective compartments.

As shown, the counters are operated by a rod 75 having rollers 76 engaging and supporting the counter levers 77, 77A, 77B etc. in a normally inoperative position (see Figure 15), which rod is mounted to slide up and down in suitable brackets 78 and is actuated by a cam 80 fixed on a shaft 81 journaled in the sorter head 10; the shaft is operatively connected to the shaft 29 in a manner to be described later, and rotates one revolution for every revolution of the shaft 29 so that the rod is lowered and raised once for each revolution of the shaft 29; springs 89 tied to the counter levers and to pins 88 (see Figure 15) and tensioned therebetween, pull the counter levers downwardly as the rod 75 lowers, to actuate the levers and register one count on the counters. With the lever of each counter co-operates a dog 85 mounted to swing on a bracket 86 and formed at the upper end to be engaged by the free end of the counter lever so as to normally arrest its downwardly swinging movement upon the lowering of the rod 75; the dogs, which are normally held in the position shown in Figure 15 by the action of tensioned springs 89 and pins 91, are swung clear of the path of the counter lever by air pistons, three of which are shown designated by 90, 90A and 90B. Thus, while the rod lowers and rises for each revolution of the shaft 29, each air piston may operate to release the corresponding counter lever, in a

manner more particularly described herein-after.

The cards being carried forwardly between the feed rollers 15 after leaving the 5 perforated plate 32, will continue until separately removed from between the feed rollers to be directed or discharged into their respective compartments, and the cards may thus be removed by the action of deflecting plates 10 93, 93A, 93B etc., fixed respectively, to cross-wise shafts 94, 94A, 94B etc., journalled in a frame 82, which plates are singly turned upwardly to present an inclined surface in the path of an advancing card. In a manner to be explained presently, each card leaving the sorter head is destined to a certain compartment, and the corresponding deflecting plate will turn just in advance of this card and will close immediately after the 15 card has been removed from the feed rollers so as not to interfere with the passage of another card destined to a compartment farther on.

Co-operating with counter levers 77, 77A, 25 77B etc., are levers 96, 96A, 96B etc., respectively, pivoted as at 97, 97A, 97B respectively, on a standard or board 98, the levers being formed to engage in slots 99 through each of the counter levers (see Figure 15), so that 30 the levers 96, 96A, 96B etc., will be swung downwardly about their pivotal points 97, 97A, 97B etc., respectively, as and only when the corresponding counter levers 77, 77A, 77B etc., respectively, are allowed to swing downwardly. From the levers 96, 96A, 96B etc., are pivotally suspended trip rods 95, 95A, 35 95B etc., respectively.

Mounted adjacent and in an axis parallel with the longitudinal axis of the machine, 40 are two endless chains 100 riding on tracks 10A supported on cross members 10B, and carrying spaced blocks or carriages 101, the function of which is to cause the deflecting plate of one of the compartments 93, 93A, 45 93B etc., to be turned into the path of an advancing card. The chains may be made to any suitable conventional design, comprising links 100A (see Figure 13) pivotally connected together by rollers or pins 100B riding on the track 10A and spaced to turn on the sprockets 109.

As shown the blocks 101 have a number of cams 102 mounted on a hinge rod 103 to swing within notches 104 made in a member 55 105, the rod 103 being mounted in blocks 106 depending from and below the member 105; the cams are separately and normally held in engagement with the member 105 by springs 108 tensioned between the lower ends 60 of said cams and an extension 108A from the member 105.

The endless chains are trained around sprockets 109, two of which are fixed to the shaft 19A and lie below the rods 95, 95A, 65 95B etc., and the blocks 101 are each secured

at either end to one of the chains; the cams 102 of each block are spaced to align with the rods 95, 95A, etc., and these are made long enough to engage the cams when the rods are lowered upon the swinging downwardly of the counter levers, but to normally clear the cams when the counter levers are in their normal position.

Each block or cam carriage 101 is provided with means for independently locking the 75 cams in their operative or swung position and to release the cams after the swung cams have separately performed their function. The cams are thus locked by a bolt 111 (see Figure 6) mounted to slide under and parallel with the hinge pin 103, the bolt having projections 112 sized to engage or slide into notches 110 formed in one edge of each cam below its pivotal point.

The bolt 111 is moved to lock one or more 80 of the cams 102 when swung into operative position, by a lever 115 pivoted as at 116 to the carriage and formed to slidably engage in a hole 117 through one end of the bolt; the lever 115 in turn is formed to slidably engage in an arcual slot 118 through a horizontally arranged lever 114 pivoted to the carriage as at 119; from the lever 114 project two rollers 120 and 121. The bolt is thus moved to lock or unlock any of the cams 90 when in operative position, accordingly as to whether the lever 114 is swung one way or the other. When the lever is in one position, say the locking position, the projections 112 in the bolt engage in the notches 110 of 95 the cams, now swung in operative position, and when the lever is in the other, or normal position, the projections clear the notches permitting of the cams to swing back to normal 100 position under the action of the springs 108. 105

In order that the lever 114 may be swung to first lock, and then unlock the cams, a clip 122, formed substantially as shown in Figure 23, is positioned to be engaged by the rollers 121 and 120 as the carriage travels forwardly with the endless chains 100. As shown, the clip terminates at the forward end in a rounded or curved portion 122A projecting forwardly so as to present an inclined 110 face in the path of the rollers on the advancing carriage. Thus, as the carriage advances, the roller 121 first engages the portion 122A and the lever 114 is swung in such a way as to cause the bolt 111 to be moved outwardly to unlock the cams; when the carriage has moved farther ahead on its course, the roller 120 now engages the portion 122A and the lever is swung inwardly, causing the bolt to be moved so as to lock the cams.

On each of the shafts 94, 94A, 94B etc., is 115 fixed a cam or clip 124 formed substantially as shown in Figure 24, the clips being staggered (see Figure 2) so as to each be in alignment with only one of the carriage cams 102; the clips are thus positioned to lie in 120

the path of and may be engaged by the carriage cams when swung and locked in operative position. As shown, the clips 124 are formed at one end with a rounded or curved portion 124A to present an inclined face in the path of a swung cam of the advancing carriage, the function of each clip being to cause the particular shaft to which it is fixed to be rotated and thus turn the particular deflecting plate into the path of the next advancing card. A second clip 125 is also fixed to each of the shafts 94, 94A, 94B etc.; these clips are all disposed in one line and formed with a curved portion 125A (see Figure 25) to present an inclined face in the path of the next advancing carriage, the function of these clips being to turn each deflecting plate back into normal or horizontal position and thus allow the next advancing card an unobstructed path to a compartment farther on. Thus, a cam 102 is provided for each compartment, and the particular clip 124 fixed to the shaft mounting the deflecting plate above the particular compartment, is positioned in line with and only that particular cam, so that the function of any one cam 102, when swung into operative or locked position, is to engage its particular clip 124 and turn the deflecting plate of the particular compartment into which an advancing card is to be directed and stored. The clips 124 and 125 may be mounted on their respective shafts as with blocks 139 (see Figure 28) the clip fitting into a recess 139A.

As shown, particularly in Figure 1, the shaft 29 has fixed thereto a sprocket 137 driven from a sprocket 137A of equal diameter, through a chain 138, the sprocket 137A being fixed on the shaft 40; on the shaft 40 is fixed a second sprocket 139 driven from a sprocket 139A of equal diameter, through the chain 140B, the sprocket 139A being fixed on the shaft 19A; thus, for every revolution of the shaft 19A, that is for every complete stroke of the feed knives 16, the shafts 40 and 29 will both rotate one revolution, the cams 39 operating at the same time to lower the block 30 and allowing the same to rise, alternately, while the cam 28 operates to lower the gate 21 and to allow the same to rise, alternately.

On the shafts 29 and 81 are fixed, respectively, the sprockets 140 and 140A, of equal diameter, and a chain 141 trained therearound, so that for every revolution of the shaft 29, and therefore for every complete stroke of the feed knives 16, the shaft 81 is turned one revolution and the cam 80 operates to lower and raise the rod 75.

On the drive shaft 141A, driven from any suitable source (not shown), are fixed worms 142 meshing with worm gears 143 fixed on a number of shafts 15A mounting the feed rollers 15; on the first two feed roller shafts

are fixed gears 144 meshing with a gear 144A fixed on the shaft 19A; power is transmitted from the second gear 144 to the last of the gears 143 to be driven from the drive shaft, by intermediate gears 145 operating and disposed as shown, so that the feed rollers 15 and the shafts 19A, 40, etc., are all driven from the same drive shaft.

In a machine constructed in accordance with this invention, a sorter can be used in conjunction with counters to form a unit and thus count the number of cards going into each sorter compartment, and this unit used singly or with a tabulator.

This combination of a sorter with a tabulator may be effected in the following manner, having reference particularly to Figures 17 to 21: the pipes or air lines 70 from the plate 32 are connected to the tabulator 130, each of such lines operating one counter; from the lines leading to each horizontal row of counters on the tabulator, are branched off an equal number of lines 70A leading to a common line 70B leading to one of the sorter counters, a suitable system of valves, shown diagrammatically as 132 in Figure 21, being interposed between the lines 70A and the line 70B; all of the lines 70 in any one horizontal row may thus be made to communicate with one sorter counter, and a sorter counter is provided for every such horizontal row of lines 70; as shown, the system of valves comprises what might be called a valve board 133 on which are mounted a number of valves or more particularly rods 134, turning in cross members 135 which are in effect valve casings; the pipes 70A are all connected to the members 135, that is the lines 70A in each horizontal row of such lines are each connected to a cross member, and there are as many rods 134 as there are lines in any horizontal row; each rod has holes 136 bored therethrough and spaced to be in alignment with all of the lines 70A in any vertical row of such lines; by turning any rod or valve 134 by its lever 134A as by hand so as to allow air to pass through their holes or ports 136, and closing the other valves, the air lines 70A in any vertical row of such lines become all connected to as many sorter counters and the sorter thus operated to count the punched holes in any vertical lines on a card while at the same time, the tabulator is continuously operating to count the total number of holes in the card.

By providing a valve 70C in each of the lines 70B, the corresponding counter may be made inoperative.

Figures 28A to 30 illustrate the application of my invention to an adding machine, the adding machine 150, of conventional design, being secured to the standards 31 by any suitable means, such as removable cleats 151 forming with extensions 152 from the stand-

ards 31, sockets adapted to receive the legs 153 of the adding machine (see Figure 30).

Air pistons 154 are operatively connected to the perforated plate 32 or more particularly to the tubes 70, and are shown mounted in a wood head 155 secured under the machine so that the piston plungers 156 may clear and engage the correspondingly spaced keys 157 of the adding machine. The pistons are retained in their spaced relation in the wood block which is bored vertically to receive the same, the block being enclosed in a hollow casting or box 158 secured to the machine. Springs 159 are positioned above the pistons, below a removable plate 160 secured to the casting, and allow the pistons to move upwardly to a limited extent to thus reduce the impact upon the keys of the adding machine. Preferably, each plunger is forced back into its cylinder by a coil spring 161 compressed between the bottom casting and a shoulder 162 fixed to the plunger (see Figure 29).

What I claim is:

- 25 1. In a sorter-counter machine and the like, a card box for the punched cards, means forming a path for the cards from said box and operating to move the cards forwardly in said path, means operating to discharge the cards successively from said box into said path, means operating to momentarily stop a card in said path, a block formed with a cavity operatively connected to a source of a fluid under pressure and adapted 30 to engage a card thereunder, a valve interposed between the source and said cavity, means associated with said valve operable to close and open the source to said cavity, locking means co-operating with said valve 35 operating means operable to releasably lock said valve operating means when said valve is closed and card-operated means co-operating with said locking means operable to release the same as said block engages with 40 the card.
- 45 2. In a sorter-counter machine and the like, a card box for the punched cards, means forming a path for the cards from said box and operating to move the cards forwardly in said path, means operating to discharge the cards successively from said box into said path, means operating to momentarily stop a card in said path, a block formed with a cavity operatively connected to a source of 50 a fluid under pressure, and movable toward and away from said path, a valve interposed between the source and said cavity, a lever operatively connected to said valve and operable to open and close the same, spring-55 actuated locks co-operating with said lever and normally locking the same when said valve is closed, and card-actuated means co-operating with said locks and operating to actuate the same to unlock said lever as said 60 block moves toward said path.

3. In a sorter-counter machine, a card box for the punched cards, means forming a path for the cards from said box and operating to move the cards forwardly in said path, knives feeding the cards successively into said path, storing compartments for the cards arranged along said path, card-removing means associated with said compartments and independently operable to remove the cards from said path whereby the same may be discharged into said compartments, carriages travelling in an endless path, cams mounted on said carriages operable to actuate said card-removing means to discharge the cards into said compartments, rods independently movable into the path of said cams to operate the same, levers suspending said rods and independently swingable to bring said rods into the path of said cams, pivoted means operatively connected with said levers, means normally in the path of said pivoted means adapted to check their swinging movement and selectively operable to move out of their path, and means co-acting with said pivoted means operating to allow the same to swing and to bring same back to normal position for each complete stroke of said knives.

4. In a sorter-counter machine, a card box for the punched cards, means forming a path for the cards from said box and operating to move the cards forwardly in said path, knives feeding the cards successively into said path, storing compartments for the cards arranged along said path, card-removing means associated with said compartments and independently operable to remove the cards from said path whereby the same may be discharged into said compartments, carriages travelling in an endless path, cams mounted on said carriages operable to actuate said card-removing means to discharge the cards into said compartments, rods independently movable into the path of said cams to operate the same, levers suspending said rods and independently swingable to bring said rods into the path of said cams, spring-operated levers operatively connected with said first-mentioned levers, means co-acting with said spring-operated levers and operating to allow the same to swing upon each complete stroke of said knives, dogs co-acting with said spring-operated levers and normally in the path thereof, and means co-acting with said dogs selectively operable to move said dogs out of the path of said spring-operated levers.

5. In a sorter-counter machine, a card box for the punched cards, means forming a path for the cards from said box and operating to move the cards forwardly in said path, knives feeding said cards successively into said path, storing compartments for the cards arranged along said path, card-removing means co-operating with said compartments

- ments and independently operable to remove said cards from said path whereby the same may be discharged into said compartments, carriages travelling in an endless path, cams mounted on said carriages operable to selectively actuate said card-removing means to discharge the cards into said compartments, trip rods independently movable into the path of said cams, levers suspending said rods and independently swingable to lower said rods into the path of said cams, pivoted means operatively connected to said levers and independently swingable to lower said rods into the path of said cams, means co-acting with said pivoted means operating to lower and raise the same for every complete stroke of said knives, dogs normally in the path of said pivoted means, and air-operated means cooperating with said dogs selectively operable to actuate the same out of the path of said pivoted means.
6. In a sorter-counter machine and the like, a card box for the punched cards, means forming a path for the cards from said box and operating to move the cards forwardly in said path, means operating to discharge the cards successively from said box into said path, means operating to momentarily stop a card in said path, a block formed with a cavity operatively connected to a source of a fluid under pressure and adapted to engage a card thereunder, a valve interposed between the source and said cavity, means associated with said valve operable to close and open the source to said cavity, locking means co-operating with said first mentioned means operable to releasably lock said first mentioned means when said valve is closed, and spring-held plungers slidably mounted in said block, card operable to engage with said locking means and release the same.
7. In a sorter-counter machine and the like, a card box for the punched cards, means forming a path for the cards from said box and operating to move the cards forwardly in said path, means operating to discharge the cards successively from said box into said path, means operating to momentarily stop a card in said path, a block formed with a cavity operatively connected to a source of a fluid under pressure, and movable toward and away from said path, a valve interposed between the source and said cavity, a lever operatively connected to said valve and operable to open and close the same, spring-actuated locks co-operating with said lever and normally locking the same when said valve is closed, and spring-held plungers slidably mounted in said block, card operable to engage with said locks and operating to actuate the same to unlock said lever as said lock moves toward said path.
8. In a sorter-counter machine and the like, a card box for the punched cards, means forming a path for the cards from said box and operating to move the cards forwardly in said path, means feeding the cards successively into said path, storing compartments for the cards

arranged along said path, card removing means associated with said compartments and independently operable to remove the cards from said path whereby the same may be discharged into said compartments, carriages travelling in an endless path, cams pivotally mounted on said carriages operable to actuate said card removing means to discharge the cards into said compartments, 5 springs between said cams and carriages resiliently retaining said cams in a normal or inoperative position, means independently movable into the path of said cams to actuate the same, means operatively connected 10 with said last-mentioned means independently operable to bring the same into the path of said cams selectively, and a slidable locking bolt on each of said carriages co-acting with said cams and releasably locking 15 the same in operative position.

12. In a sorter-counter machine, a card box for the punched cards, means forming a path for the cards from said box and operating to move the cards forwardly in said path, 20 knives feeding the cards successively into said path, storing compartments for the cards arranged along said path, card removing means associated with said compartments and independently operable to remove the 25 cards from said path whereby the same may be discharged into said compartments, carriages travelling in an endless path, cams pivotally mounted on said carriages operable to actuate said card removing means to discharge the cards into said compartments, 30 springs between said cams and carriages resiliently retaining said cams in a normal or inoperative position, means independently movable into the path of said cams to actuate the same, means operatively connected 35 with said last-mentioned means independently operable to bring the same into the path of said cams selectively, each of said cams having a notch, and a slidable locking bolt on each 40 of said carriages formed to engage in the notches in said cams when said cams are in operative position whereby said cams are releasably locked in operative position.

13. In a sorter-counter machine, a card box for the punched cards, means forming a path for the cards from said box and operating to move the cards forwardly in said path, knives feeding the cards successively into said path, storing compartments for the cards 50 arranged along said path, card removing means associated with said compartments and independently operable to remove the cards from said path whereby the same may be discharged into said compartments, carriages travelling in an endless path, cams pivotally mounted on said carriages operable to actuate said card removing means to discharge the cards into said compartments, 55 springs between said cams and carriages resiliently retaining said cams in a normal or in-

operative position, means independently movable into the path of said cams to actuate the same, means operatively connected with said last-mentioned means independently operable to bring the same into the path of said cams selectively, each of said cams having a notch, and a lever-actuated locking bolt on each of said carriages slidable between an inoperative and an operative position, said bolt being formed with spaced projections disposed to engage in the notches in said cams when said cams are in operative position.

14. In sorter-counter machines, a card box for the punched cards, means forming a path for the cards from said box and operating to discharge the cards successively from said box into said path, means operating to momentarily stop a card in said path, a block formed with a cavity operatively connected to a source of a fluid under pressure and adapted to engage a card thereunder, a valve interposed between the source and said cavity, means associated with said valve operable to close and open the source to said cavity, and means between said block and valve operating means normally locking said valve operating means and card-operable to release the same as said block engages with the card.

15. In sorter-counter machines, a card box for the punched cards, means forming a path for the cards from said box and operating to move the cards forwardly in said path, means operating to discharge the cards successively from said box into said path, means operating to momentarily stop a card in said path, a block formed with a cavity operatively connected to a source of a fluid under pressure and adapted to engage a card thereunder, means for moving said block to engage the card for every stroke of said card-discharging means, a valve interposed between the source and said cavity operable to open the source to said cavity for every stroke of said card-discharging means, and means locking said valve and card-operable to release said valve as said block engages with the card.

Signed at Ottawa, this 1st day of November, 1929.

FERNAND BELISLE.
